UNITED STATES PATENT OFFICE.

WILLIAM I. THOMPSON, OF STONEHAM, MASSACHUSETTS, ASSIGNOR OF ONE-THIRD TO ANTHONY M. LUX AND ONE-THIRD TO WALTER J. LUX, BOTH OF WOBURN, MASSACHUSETTS.

ELECTRICALLY-HEATED TOOL.

1,157,343.

Specification of Letters Patent.

Patented Oct. 19, 1915.

Application filed February 5, 1915. Serial No. 6,253.

To all whom it may concern:

Be it known that I, WILLIAM I. THOMPSON, a citizen of the United States, and resident of Stoneham, in the county of Middlesex and State of Massachusetts, have invented certain new and useful Improvements in Electrically-Heated Tools, of which the following is a specification.

This invention relates to electrically heated tools, and particularly to such tools adapted for use in finishing external parts of boots and shoes.

The invention has for its object to provide a tool of this character of simple and durable construction adapted to perform rubbing operations on a boot or shoe, and preferably adapted also to perform percussive operations.

The invention consists in the improvements which I will now proceed to describe and claim.

Of the accompanying drawings forming a part of this specification: Figure 1 represents a side elevation of a tool embodying my invention; Fig. 2 represents a longitudinal section on line 2—2 of Fig. 1; Fig. 3 represents a section on line 3—3 of Fig. 1; Fig. 4 represents a sectional view of the tool body; Figs. 5 and 6 represent enlargements of portions of Fig. 2.

The same reference characters indicate the same or similar parts in all the views.

My improved tool includes a heating unit including a spool composed of a core 12 of heat-conducting metal having an outer flange 13 integral with said core and an inner flange 14, preferably of insulating material such as mica, and formed by assembling centrally perforated mica disks on the reduced end portion 16 of the core. The flange 14 abuts against a shoulder 19 on the core, and is confined against said shoulder by a washer 20 applied to the reduced portion 16 and rigidly secured by upon the spool 12 and the flanges there-

of are wound coils 25 of resistance wire, the coils being all formed from a single length of wire and insulated from each other preferably by layers of mica 25^a applied during the winding operation. The outer end convolutions of the wire are insulated from the flange 13 by a mica washer 15. The resistance wire coils are surrounded by a cylindrical metal casing 26 which may be secured to the spool by one or more screws 27 engaging one of the spool flanges.

The casing 26 is provided with a shank composed of an air-cooled spider formed by inclined radial arms 29 integral with the casing, and a tubular portion 28 connected with the outer ends of the arms. The spider portion of the shank permits a free circulation of air around the arms composing it, so that the tubular portion 28 is not liable to be overheated.

30 represents a wooden handle mounted on the shank 28 and protected against injurious heat by the air-cooled spider. The bore of the handle which receives the shank 28 has a mica bushing 31, at the ends of which are mica enlargements 32 bearing against shoulders at opposite ends of said bore, said bushing and enlargements additionally protecting the handle against heat.

The terminals of the wire forming the resistance coils 25 are conducted through the insulating flange 14 to binding posts 33 embedded in said flange and projecting into the air-cooled spider, and at said posts are connected with suitably insulated leading wires 34 extending through the tubular shank portion 28. The spaces between the spider arms 29 permit free access to the binding posts 33. The wires 34 extend to a cavity 36 in the outer end of the handle, and through an inclined orifice 37 in the handle. The cavity 36 is closed by a plug 38 secured by screws 39. The passage 37 is inclined to permit the leading wires to pass laterally through the handle without being abruptly bent at any point and without liability of the injurious kinking of the usual flexible extensions of said leading wires which are connected with the source of electrical energy. The leading wires are each preferably composed of a plurality of intertwined strands of fine No. 60 wire forming what is known as pig-tail wire and insulated by windings of asbestos cord, each composed of two layers or courses, one

wound in the opposite direction from the other.

The spool 12 and its flanges 13 and 14, and the casing 26, constitute a rigid holder 5 for the resistance wire, said holder carrying the coupling member 22 and the handle, and closely fitting the socket hereinafter referred to, formed in the body.

The tool body 24 has a cylindrical socket 10 40 open at the inner end of the body and formed to snugly and removably fit the casing 26. The partially cylindrical portion of the wall of said socket is adapted to serve as a hammer head by which the operator 15 can perform various percussive as well as rubbing operations on the external surface of a boot or shoe. Said portion is relatively thick and is reinforced or backed by the casing 26, which also has a substantial thickness, and in effect is a part of the hammer head.

The rubbing or burnishing portions of the body are preferably formed by a flat face 42 forming one side of the body and extending 25 from end to end of the body, and an inclined marginal face 43 which intersects the margin of the face 42 at a substantially acute angle, and is substantially U-shaped and extends transversely across the outer end 30 of the body and longitudinally along the sides thereof. In other words, the faces 42 and 43 form a thin-edged lip having a U-shaped edge extending lengthwise and across the body, one side of said lip formed 35 by the face 43 being inclined, and the other side flat. A considerable portion of each of said faces is in close proximity to the heating unit and adapted to be quickly heated thereby and to conduct heat to other portions 40 of said faces.

The body is detachably secured to the spool by the engagement of the stud 22 with the cavity 23, and the outer face of the spool flange 13 abuts against the inner end of the 45 socket 40, so that heat is directly conducted to the body by said flange as well as by the casing 26. Since the burnishing faces extend from end to end of the body, their inner end portions are in close proximity not 50 only to the heating unit, as above stated, but also to the handle. The length of the tool as a whole is therefore reduced to the minimum, so that the muscular exertion and fatigue of the operator in manipulating the tool are correspondingly reduced.

The body formed as shown is adapted to act on broad surfaces and on the sides of creases such as the crease between the welt and upper of a shoe.

The portion of the body 24 containing the socket 40 constitutes a tubular end portion, and the portion at the inner end of the socket constitutes a solid end portion, which contains the coupling member 22 and is uniformly affected by heat conducted from the

resistance wire through the holder 12 and coupling member 22. The burnishing face 42 is formed partly on the solid portion and partly on the tubular portion. The heat-conducting coupling member 22 is therefore 70 located centrally with relation to said face, so that the heat conducted thereby is quickly and uniformly distributed throughout the entire area of said burnishing face. The same statement is applicable to the burnish- 75 ing face 43.

The casing 25 inclosing the heating unit and closely fitting the body socket 40, and the air-cooled spider and tubular shank portion united to said casing, constitute a strong 80 and durable means for holding the handle 30 in close proximity to the body 24, preventing the heating of the handle, and reinforcing the tubular portion of the body. Said casing and the heating unit are adapted 85 to be applied to and removed from the body as a single part, and are readily separable to permit access to the resistance wire.

Having described my invention, I claim:

1. An electrically heated tool comprising 90 a body having a burnishing face or faces and a cylindrical socket which is open at one end of the body, an electrical heating unit, a cylindrical casing detachably secured to and inclosing said unit and provided with 95 a shank composed of spaced arms joined to the casing and forming an air-cooled spider, and a tubular portion joined to said arms and spaced from the casing and heating unit thereby, a handle mounted on said tubular 100 portion and held thereby in relatively close proximity to the said casing and unit, and spaced therefrom by said spider, and conducting wires extending through said tubular portion and handle, the heating unit 105 comprising a resistance wire whose terminals project into said spider and being provided with means within the spider for connecting said conducting wires with said terminals, the heating unit and casing being 110 insertible as a single part in said socket, means being provided for detachably connecting the body and heating unit.

2. An electrically heated tool comprising 115 a body having a burnishing face or faces, said body being tubular at one end portion and solid at the opposite end portion, the tubular portion having a cylindrical socket which is open at one end of the body, an electrical heating unit comprising a spool 120 having inner and outer flanges, the outer flange being provided with outwardly projecting binding posts, and a resistance wire wound upon the spool, the terminals of said wire extending through the outer flange and engaging said binding posts, means being provided for detachably connecting the spool and body, a cylindrical casing detachably fitting said socket, seated upon and extending between said flanges, and detachably 125 130

- secured to the spool, said casing being provided with a shank composed of spaced arms forming an air-cooled spider, and a tubular portion projecting from said spider, a handle mounted on the tubular portion of the shank with its inner end in close proximity to the body and heating unit, and spaced therefrom by the spider, and conducting wires extending through the shank and connected with the resistance wire terminals at said binding posts, the spaces between the spider arms not only permitting a free circulation of air to cool the shank, but also permitting access to said binding posts.
- 5 3. An electrically heated hammering and burnishing tool comprising a body having a cylindrical socket which is open at one end of the body, the opposite end being closed, a portion of said socket wall having a rounded external face capable of use as a hammer 20 head, while another portion of said wall has a flat burnishing face extending from end to end of the body, and a U-shaped burnishing face inclined relatively to said flat face and intersecting the latter to form an acute 25 angled U-shaped burnishing edge extending along both sides of the body and across its outer end, and an electrical heating unit removably inserted in said socket.
- 10 In testimony whereof I have affixed my 30 signature, in presence of two witnesses.
- 15 WILLIAM I. THOMPSON.
